UNITED STATES PATENT OFFICE.

WILLIAM PAULI, OF NORTH SACRAMENTO, CALIFORNIA.

RUBBER BAND CATAULTING TOY.

Application filed December 7, 1927. Serial No. 238,386.

My invention relates to improvements in rubber band catapulting devices, the same being in the form of a toy pistol, which when the trigger member thereof is released, a 5 rubber band stretched on the pistol body, and in association with the trigger, will be catapulted by its own tensional force, through the air.

The main object of my toy catapulting device 10 resides in providing a simple device in simulation of a pistol, with which a rubber band may be associated, and projected through the air when released therefrom.

Other very novel objects and advantages 15 of my novel toy, will become apparent as the same is better understood from the specification and claim to follow.

In the drawing:—

Fig. 1 discloses a side elevation in partial 20 sectional view, and

Fig. 2 is a top plan view of the toy as represented in Fig. 1.

Now for a more detail disclosure of my novel catapulting device, I refer to the drawing, in which like numerals designate like 25 parts. A cylindrical barrel 1, may be formed at its outer end with an inwardly extending bore to simulate the bore of a real fire arm. The rear end of the barrel is bifurcated at 30 2, the furcations of which are preferably curved as at 3.

The bight of the bifurcation is inclined inwardly, at 4, while a pocket 5 is formed in the top of the barrel immediately adjacent 35 the upper end of the inclined bight 4. The outer end or muzzle portion of the barrel is formed with a transverse rearwardly curved groove 6, while at the opposite end portion of the barrel, a depending handle 7 is provided.

This handle is formed to simulate the handle of a real pistol, and is formed at the upper portion of its inner edge with a horizontally extending bore 8. A stem 9 is provided with an enlarged head 10, while the stem portion projects through the handle, and centrally thru the bore 8 to project a substantial distance externally thereof. The opposite end of the stem is provided with an 50 arcuate finger piece 11, while a coiled com-

pressible spring 12 is disposed around the stem, so that one end thereof will engage the inner side of the finger piece, while its opposite end will engage the portion of the handle, at the inner end of the bore 8. 55

A hammer 13 is pivoted at 14 between the furcations, and is formed with a finger engaging construction 15, while a projecting flat faced member 16 is provided, and adapted to engage an explosive cap disposed 60 within the pocket 5. It will now be seen that when a rubber band of the desired thickness and elasticity is disposed at one end of the barrel within the groove 6, and then stretched the length of the barrel, may be 65 sprung over the hammer 13 at a point substantially below the center line of pull, the device will be set.

Thus, when the stem 9 is forced inwardly by pressure against the finger piece 11, the 70 head 10 will engage the inner edge of the finger engageable portion of the finger engageable portion 15, to fasten it a sufficient movement due to cause the band 17 at its rearward end, to be lifted above the longitudinal axis. 75

This will cause the projection 16 to be snapped into the pocket 5, and against a pre-disposed explosive cap therein, which cap will be exploded besides completely releasing the band from the rear portion of the barrel, from where it will catapult by reason of its own tensional force. 80

My improved rubber band catapulting toy is of very simple construction, yet very positive in function, and aims to provide a novel 85 toy for children.

Having thus described my invention, what I claim as new is:—

A toy of the class described comprising a 90 body simulating a pistol, said body including an elongated barrel portion and a depending handle at one end thereof, a hammer pivotally secured to the barrel at its handle end, said handle being provided with an 95 opening extending transversely inwardly from the inner edge and adjacent the barrel, said handle being provided with a reduced opening continuing the first mentioned opening transversely through the handle, a 100

stem slidably disposed through said openings and provided with a head at each end thereof, a coil spring interposed between the inner end of the enlarged opening and the head at the inner end of the stem, the head at the opposite end of the stem being adapted for engaging and moving the hammer and

a rubber band adapted to be stretched from the muzzle end of the barrel over the said hammer and to be catapulted when the hammer is released by the operation of the said stem. ¹⁰

In testimony whereof I affix my signature.
WILLIAM PAULI.
